Primary Examiner — Patricia A Palasik(74) *Attorney, Agent, or Firm* — Michael J. Feigin, Esq.; Feigin and Fridman LLC(57) **CLAIM**

The ornamental design for a spinner, as shown and described.

DESCRIPTION

FIG. 1 shows a top and side perspective view of a spinner. FIG. 2 shows a reverse bottom and side perspective view thereof.

FIG. 3 shows a first elevation view thereof.

FIG. 4 shows a second elevation view thereof.

FIG. 5 shows a third elevation view thereof.

FIG. 6 shows a fourth elevation view thereof.

FIG. 7 shows a top plan view thereof.

FIG. 8 shows a bottom plan view thereof; and,

FIG. 9 shows a sectional view cut along section line 9-9 of FIG. 7.

The broken lines represent portions of the spinner which form no part of the claimed design.
